UNITED STATES PATENT OFFICE.

FREDERICK A. LUNDAHL, OF EAST MOLINE, ILLINOIS.

RAILWAY TRACK AND METHOD OF FORMING THE SAME.

Application filed April 26, 1926. Serial No. 104,549.

This invention relates to railway tracks and method of forming the same.

An object of this invention is to provide a miniature railway track of internal formation, including crossties and rails, for use in connection with toy vehicles having flanged wheels adapted to cooperate with the rails of said track, and more particularly for use in connection with a toy vehicle of the character disclosed in my companion application filed of even date herewith.

Another object of the invention is to provide a novel process of making a track of the above character, which consists in cutting out an elongated plate of heavy gauge sheet metal, forming rails therein by pressing into said sheet longitudinally arranged spaced parallel corrugations and cutting out the material at intervals between the rails and on the outer sides thereof to provide crossties, and bending the marginal edges of said crossties to provide a channel-shaped formation.

Another object of the invention is to provide a plurality of track sections of the character above referred to, together with novel means for connecting individual sections in such a manner as to aline the rails thereof and rigidly and detachably connect the track sections in a simple and effective manner.

Still another object of the invention is to provide a track of integral metallic formation, wherein the crossties project outwardly beyond the rails, in conjunction with a continuous third or conducting rail which may be secured to the projecting ends of the cross ties and insulated therefrom, to adapt the track for use in connection with toys which are propelled by electricity.

Other and further objects of the invention will more clearly and fully appear from the description and claims herein-after following.

In the drawings, Fig. 1 is a fragmentary top plan view of a track section after the same has been stamped or pressed to provide parallel longitudinal corrugations, and indicating in dotted lines the portions which will be cut out to provide the crossties. Fig. 2 is a fragmentary top plan view of a plurality of sections of the track after the crossties and rails have been shaped to the

required form and showing the means for detachably connecting the two sections together. Fig. 3 is a bottom plan view of the track sections shown in Fig. 2, and disclosing the means for effecting connection between the two track sections as viewed from the undersurface of the track. Fig. 4 is a transverse, sectional view of the invention substantially upon the line 4—4 of Fig. 2. Fig. 5 is an enlarged, perspective view of the connecting plate utilized in effecting alinement and juncture between the two track sections. Fig. 6 is an enlarged perspective view of the latch which cooperates with the connecting plate to secure the parts in position. Fig. 7 is a top plan view of a track section of a character similar to that disclosed in Figs. 2, 3 and 4, showing the track section provided with a third or conducting rail insulated from the track proper. And Fig. 8 is a sectional view substantially upon the line 8—8 of Fig. 7.

The herein described process of making an integral track including rails and crossties consists in cutting out an elongated plate of heavy gauge sheet metal common in commercial use of suitable width and length, and introducing said plate into a suitable press having dies of such character as to form either separately, or successively, two spaced longitudinally extending parallel corrugations indicated in Fig. 1 at 9—9, it not being thought to be necessary to illustrate the particular character of dies necessary to produce the corrugations as dies for producing corrugations are well known and may be made up readily as required. In this connection, the corrugations may be formed separately by two portions of a die having means for making a single corrugation, or may be formed by a die having means for forming the two corrugations successively, that is, one corrugation should be completely formed before the other is begun, because if the two corrugations are made simultaneously the metal may be torn, although in certain grades of metal used the same may be drawn to the desired extent so as to permit the corrugations to be made simultaneously without tearing of the metal. Although it is preferred to make the corrugations either separately by separate dies, or successively by the same die, it should be

understood that the two corrugations could be formed simultaneously with certain grades of metal which can be drawn to the desired extent without tearing.

5 The blank thus corrugated is then cut out upon the dotted lines shown in Fig. 1 by a suitable press so as to provide a series of transversely extending substantially rectangular cut out portions between the rails spaced apart a suitable distance to provide material for the crossties indicated at 10-10, and to provide extensions of the crossties at the outer sides of the rails as indicated at 11-11, the cut out portions 10 and 11 preferably being made simultaneously.

10 The crossties are then formed in channel shape by bending the longitudinal marginal edges of the portions 10 in a direction opposite to the rails, and the side and end marginal edges of the extensions 11 are also bent in the same manner, this operation being accomplished by suitable shaping dies, either simultaneously with the cutting out process, or separately if desired, it being noted that a slight excess of material is provided as indicated at 12 in the corners of the cut out portions, and the outer ends of the extensions 11 have their corners 25 rounded off as indicated at 13. By providing the excess of metal indicated at 12, when the portions 10 of the ties are formed, there is no tearing of the material due to bending of the marginal edges, and by rounding off 30 the outer corners of the extensions 11 an excess of metal after the extension has been formed is avoided.

15 The track section which is produced by the above described process comprises the channel-shaped crossties 14 having bent flanges 15 on the marginal edges thereof which afford the channel formation, the crossties 14 terminating adjacent the base of the corrugations 16-16, providing the parallel rails, and the extensions 17-17 which have marginal flanges 18 providing the channel formation. The corrugations 16-16 are pressed into the metal so as to extend to one side of the main plane of the track and 20 said corrugations intersect the crossties as shown, said crossties, extensions and rails being all integrally formed.

25 In order to provide means for connecting a plurality of track sections of the character above described, the following arrangement is utilized. One of the track sections is provided with a connecting plate 20 having a flat elongated member 21 provided with lateral extensions 22-22, which are spaced apart a distance to coincide with the distance between the corrugations 16-16 of the track section, the lateral extensions having upturned longitudinally extending flanges 22a which are adapted to fit within the corrugations to provide a connecting web at

the points where the two sections are joined together. The lateral extensions have integrally connected with their ends an elongated member 23 which is spaced from the member 21 a distance corresponding to the distance between the crossties. The member 23 is provided with a pair of spaced upturned lugs 24-24, each of said lugs being provided with an aperture as indicated at 25. The member 21 is of such size as to fit snugly within the flanges 15-15, and flanges 18 of the crosstie at the end of the track section, the flanges on the lateral members 22 extending within the corrugations 16-16, which are cut off outwardly from the end tie 19, preferably at a distance approximately one-half the distance between the ties. The lateral portions 22 extend beneath the cut-off portions of the adjacent track section and the elongated member 23 is fitted within the flanges on the end tie 27 adjacent the end of the related track section.

20 The portion 21 of the connecting member is preferably secured to the tie 19 by means of spotwelding, while the portion 23 of the connecting member detachably fits within the end crosstie 27 of the adjacent section of the track. The crosstie 27 is provided with spaced apertures 28-28 adapted for the reception of the lugs 24-24, said lugs projecting above the upper surface of the crosstie 27 of the adjacent track section. Pivotedly mounted intermediate its ends upon the upper surface of the crosstie 27 is a latch 29, said latch being provided with oppositely extending latching portions 30-30 adapted to be inserted into the apertures 25 of the lugs 24, each of the latching portions 30 being slightly beveled or wedge-shaped as indicated at 310 so as to effect a tight connection to prevent accidental withdrawal of the wedging portions 30 and to secure the parts tightly together.

25 A slightly different embodiment of the invention is illustrated in Figs. 7 and 8, said embodiment including track sections of the identical character above described, but such track sections have associated therewith a third rail to adapt the track for use in connection with vehicles propelled by electricity. In said embodiment a third or continuous conducting rail 31 is provided, said rail having laterally extending securing plates 32 by which the same may be secured to the extensions 33 upon the track proper. The securing plates 32 upon the third rail 31 are spaced apart such a distance that they occur about every fourth tie of the track proper, the rail resting upon a pad of insulating material 34 disposed upon the upper surface of the extension of the track proper, an insulating pad 35 being also provided on the under surface of the extension 33, and a bolt 36 extends through the secur-

ing plate 32, and through the opening in the extension 33, the rail 31 being insulated from the track proper by the interposition of the insulating pads 34 and 35.

6 While I have herein described what I now consider the preferred manner of carrying out my invention, the same is merely illustrative, and I contemplate all changes and modifications that come within the scope of 10 the claims appended hereto.

I claim:

1. A method of making an integral track section comprising crossties and rails, consisting in cutting out an elongated blank of 15 sheet metal, forming longitudinally extending parallel corrugations in said blank to provide rails, and forming transversely arranged crossties in said blank by cutting out the metal thereof at pre-determined 20 points.

2. The method of making an integral track, comprising crossties and rails, consisting in cutting out an elongated sheet metal blank, embossing longitudinally extending parallel corrugations in said blank to provide rails, and forming crossties which extend between said rails and outwardly of 25 said rails by cutting out the metal of the blank at predetermined intervals.

3. A method of making an integral track section comprising crossties and rails, consisting in cutting out an elongated blank of 30 sheet metal, forming longitudinally extending parallel corrugations in said blank to provide rails, and forming transversely arranged crossties in said blank by cutting out the metal thereof at predetermined points,

35 and bending the marginal edges of said crossties in a direction away from the rails to provide a substantially channel formation.

4. The method of making an integral track of sheet metal consisting in cutting out an elongated blank of material; cutting 40 out portions of said blank to provide crossties, and bending the marginal edges of said crossties to form each of said crossties in channel shape.

5. The method of making pressed metal 45 tracks of integral construction consisting in cutting out a sheet of metal to define longitudinal extending rail portions and cross members arranged on both sides of said rail portions; and bending the marginal edges 50 of said cross members to form each into channel shape.

6. As an article of manufacture, an integral metallic track section having spaced, longitudinally extending parallel corrugations 60 providing rails, the material between said rails being cut out to provide crossties.

7. As an article of manufacture, an integral track section comprising spaced, longitudinally extending corrugations providing 65 rails and aligned spaced cut out portions

between said rails and outwardly of said rails to provide crossties.

8. As an article of manufacture, an integral track section comprising spaced, longitudinally extending corrugations providing 70 rails and aligned spaced cut out portions between said rails and outwardly of said rails to provide crossties, said crossties being channel-shaped in cross section.

9. In a device of the character described, 75 the combination with a plurality of metallic track sections; of connecting means secured to one of said sections and provided with elements adapted to register with means upon another of said sections to aline the meeting 80 ends of the rails of said track sections; and mechanism for rigidly but detachably securing the registering means of said track sections.

10. In a device of the character described, 85 the combination with a plurality of metallic track sections; of connecting means secured to one of said sections and provided with spaced elements adapted to register with means upon another of said sections to aline 90 the meeting ends of the rails of said track sections; and mechanism for rigidly but detachably securing the registering means of said track sections, said means being in the form of a double ended latch pivotally secured to said other section and adapted to simultaneously engage the spaced elements 95 of said first section.

11. In a device of the character described, 100 the combination with a plurality of track sections, each of which includes spaced, longitudinally extending parallel rails, and channel-shaped crossties; of a connecting member including elongated portions disposed in the end crossties of adjacent sections, and having lateral connecting members 105 spaced apart a distance corresponding to the distance between said rails, said connecting member being rigidly secured to one of said track sections and having extensions 110 detachably engaged in apertures in the other of said track sections; and a double ended latch pivotally mounted on said other track section and having engaging portions adapted to engage in apertures in the projections 115 on said connecting member.

12. In a device of the character described, 120 the combination with a plurality of track sections, each of which includes spaced, longitudinal extending parallel rails, and channel-shaped crossties; of a connecting member including elongated portions disposed in the end crossties of adjacent sections, and having lateral connecting members spaced 125 apart a distance corresponding to the distance between said rails, said connecting member being rigidly secured to one of said track sections and having extensions detachably engaged in apertures in the other of said track sections; and a double ended latch 130

pivotedly mounted on said other track section and having engaging portions adapted to engage in apertures in the projections on said connecting member, said engaging portions being beveled.

13. In an integral metallic railway track, including longitudinally extending spaced parallel rails, and integral crossties, said crossties extending outwardly of said rails; 10 and a continuous rail of conductor material mounted on the outer extremities of said crossties and insulated therefrom.

14. In a track section of the character described, comprising a metallic sheet having integral longitudinally extending parallel rails formed therein, the material of said sheet ex-

tending outwardly beyond one of said rails; and a third conducting rail mounted on the outwardly extending portions and insulated therefrom.

20

15. A metallic track section having spaced longitudinally extending parallel corrugations providing rails, the material between said rails being cut out to provide cross ties, and a rail of conducting material extending substantially parallel with the corrugations providing the rails and secured to said cross ties and insulated therefrom.

25

In witness that I claim the foregoing I have hereunto subscribed my name this 14 day of April, 1926.

FREDERICK A. LUNDAHL.
